UNITED STATES PATENT OFFICE

HENRY J. HERSEY, JR., OF SALT LAKE CITY, UTAH, AND DANIEL B. MIKESELL, OF WARSAW, INDIANA

SUPPORTING MEANS FOR FLEXIBLE TUBING

Application filed May 15, 1931. Serial No. 537,578.

This invention relates to an improved supporting means for flexible tubing, and more particularly flexible tubing of the collapsible kind used in ventilating mines, though not restricted thereto.

The principal objects of the invention are:

First. To provide simple and efficient means for supporting flexible tubing which may be inflated for conducting air or other gases under pressure.

Second. To allow the collapsing of the tubing when deflated.

Third. To guard against the early destruction of the tubing due to deterioration at the points of support.

In our experience, it has been found that the life of flexible ventilating tubing can be considerably lengthened by the simple expedient of providing two side supports, instead of a single support located at the top of the tubing, as has been the previous practice. This is brought about by the fact that in mines, and especially metalliferous mines, rapid deterioration of the tubing ensues along its crest, due to mine water, charged with injurious substances, which constantly drips down onto the tubing and causes a rotting effect upon the area of the tubing fabric in proximity to the points of attachment along the upper portion of the tubing.

In our improvement, the tubing is provided with two longitudinal side flanges, consisting preferably of several thicknesses of the material of which the tubing is made and which serve to strengthen the tubing. Spaced apart in pairs, along the length of these flanges, are eyelets, preferably of metal, and located diametrically opposite each other. Engaged in each pair of eyelets, are bails, each of these bails being preferably in two parts, and provided with a hook which may be fastened to any suitable anchorage in a mine.

The features of this invention for which the protection of Letters Patent is desired, are collectively grouped in the claims concluding this specification.

In the drawings,

Fig. 1 represents a view in perspective of

a short section of flexible tubing embodying our improvement;

Fig. 2, an enlargement of substantially the portion enclosed by the broken line 2 in Fig. 1;

Fig. 3, a cross section of a flexible tube inflated, showing the bail in elevation;

Fig. 4, a cross-section similar to Fig. 3, but showing an alternate position due to a deformation;

Figs. 5 and 6, enlargements, in perspective, of the portions enclosed by broken lines 5 and 6 in Figs. 3 and 4, respectively; and

Fig. 7, a modification in the construction of the bail.

Referring to the drawings, the numeral 10 indicates a collapsible tube made of flexible material such as a waterproof textile fabric and having the side flanges 12 preferably formed of layers 14, Fig. 2, of the fabric.

Spaced apart along the flanges 12, may be eyelets 15, preferably made of metal. Engaged in certain of these eyelets, by means of hooks 16, are hangers or bails 17 preferably formed of two parts, or wickets 17-1 and 17-2. The parts 17-1 and 17-2 are preferably so connected to each other, as to allow a certain amount of movement, as indicated in Fig. 6. For this purpose, the part 17-2 may have a substantially horizontal eyelet 18 and a substantially vertical eyelet 19. Through these eyelets passes the upper portion of the part 17-1, while a shoulder formed at 20, acts as a stop for engaging the eyelet 19 when the parts are moved toward each other, so as to prevent the bail from closing together to an undue extent. A hook 24 forms the terminus of the part 17-1 and serves to attach the bail to any suitable anchorage, such as a messenger cable 25, as indicated in Fig. 1.

It will be noted in Fig. 1, that eyelets 15 are spaced comparatively close together, while the hangers are spaced at greater intervals. This provides an excess of eyelets and permits of considerable variation in locating the bails, so as to adapt an installation to individual conditions and to the individual judgment of the user.

The substantially normal shape of the bails

17 is indicated in elevation in Fig. 3, but it frequently happens in the course of usage, that the bails become distorted, assuming a shape such as indicated for instance, in Fig. 5 4. It will be noted that when this occurs, the two parts of the bail are allowed to assume a relation such as is approximately indicated in Fig. 6, where 17-3 represents the distorted form of the part 17-2. Even with the 10 distortion, the bail still clears the inflated tubing.

If desired, the modified construction of the 15 bail illustrated in Fig. 7, may be used. In this construction the bail is made of two parts 15 27-1 and 27-2, these two parts being connected to each other by the respective eyelets 25 and 26.

A singular advantage of the bails of both 20 types is that moisture, which has a tendency to drip from the roof of the mine workings, accumulates and follows the bails from the messenger cable, but flows off from the latter substantially as indicated by the arrows 28 in Fig. 3 without touching the tubing.

25 It is to be particularly noted that the top 10-1 of the tubing is entirely free from any obstruction, and that such moisture as may strike the top of the tubing will immediately flow off without encountering any obstruction thereon and thus having no opportunity to soak into the fabric. At the same time, each bail supports the tubing at two points, so that the stress of suspension is cut in two, and as the points of attachment are located 30 in the substantially vertical portion of the tubing walls, instead of in the substantially horizontal portion at the top of the tubing walls, a greatly extended life of the tubing fabric is obtained.

40 When flexible tubing is so suspended that it has constantly the same surface uppermost, the deterioration due to the constant dripping of mine water thereon, is very considerable. By means of our improvement, this 45 evil is reduced by one-half, since the two side flanges with their eyelets are designed for turning the tubing over so that at the proper time the top and bottom are reversed. The same turning over, also reduces by sub- 50 stantially one-half, any bad effects upon the lower bends of the flanges where these join the body of the tubing.

55 Ordinarily, stresses imposed by the weight of the tubing, tend to force up the outstanding side flanges at the points of suspension, as indicated in Figs. 1 and 2, thereby putting all the wear and tear on the bent fibers of the lower part of the flanges. Now, due to that 60 property of our improvement which allows the turning over of the tubing, only about one-half of this wear and tear is manifested at any one point, since the wear is distributed over both bent portions of each flange.

65 The benefits just enumerated are realized in this invention, in addition to those proper-

ties which allow the free inflation and deflation of the tubing.

The yielding action between the two parts or wickets, 17-1 and 17-2, or 27-1 and 27-2, of which each bail is composed, allows the freedom necessary for the bail to accommodate itself to the different positions of the flexible tubing walls while passing from the deflated stage to the inflated stage, or vice versa.

70 The construction indicated in Figs. 1 to 6 is especially useful, due to the eyelets 18 and 19 being spaced apart from each other on wicket 17-2, and so arranged that eyelet 19 engages the body of wicket 17-1, while the eyelet 18 engages the transverse neck 22, which permits the eyelets to freely slide along 75 respective portions of wicket 17-1.

75 While a specific embodiment of our invention is herein shown and described, it is to be understood that various changes could be made therein without departing from the spirit and scope of the invention as defined in the claims.

80 Having fully described our invention, what we claim is:

1. Supporting means for flexible tubing, including in combination, a flexible tube having side members projecting therefrom, a bail straddling the upper portion of the tubing, and means for attaching the lower extremities of the bail to said tubing in such a manner that said tubing shall be free to allow collapsing thereof when deflated.

2. Supporting means for flexible tubing, including in combination, a collapsible tube having outwardly projecting side flanges extending longitudinally thereof, a bail extending over the upper portion of the said tube, and means for attaching the lower extremities of said bail to said side flanges so as to allow said tube to collapse freely when it is deflated.

3. Supporting means for flexible tubing, including in combination, a collapsible tube, a bail portion having an upper hook, a neck therebelow, and a lower hook; a second bail portion having an eyelet engaging said neck, and a lower hook; and means for engaging the lower hooks of both the said bail portions and said tubing at points opposed to each other and located substantially at the extremities of a diameter of said tubing.

4. Supporting means for flexible tubing, including in combination, a collapsible tube, a bail portion having its lower end attached to said tube, a neck portion at the upper end of said bail portion; a second bail portion having its lower end attached to said tubing at a point opposed to the point of attachment of the first bail portion, means for flexibly connecting the upper part of the second-mentioned bail portion to the neck of the first bail portion, and means for attaching the first bail portion to an anchorage so as to allow 120 125 130 135 140 145 150 155 160 165 170 175 180 the free collapsing of said tube when deflated.

5. In combination, a flexible tube having fastening members disposed longitudinally on both sides thereof, and hangers engaging said fastening members in such a manner as to render said tube reversible, and at the same time, to be freely inflated and deflated.

6. Supporting means for flexible tubing, including, in combination, a bail composed of 10 two parts, one part having a body and a neck extending transversely of the body, the other part having two eyelets spaced apart from each other, one eyelet engaging said body, the other eyelet engaging said neck; and a 15 flexible tube straddled by said bail, the lower portions of the bail being fastened to the sides of the flexible tube so as to render said tube reversible in the bail.

7. Supporting means for flexible tubing, 20 including in combination, a bail composed of two wickets having eyelet portions joining said wickets together, and a flexible tube straddled by said bail, the lower portions of the bail being fastened to the sides of the 25 flexible tube so as to render said tube reversible in the bail.

In testimony whereof, we sign our names hereto.

HENRY J. HERSEY, JR.
DANIEL B. MIKESELL.
